UNITED STATES PATENT OFFICE

ANDREW GAUL, JR., OF ALBANY, NEW YORK

AIR COOLED GRATE

Application filed March 1, 1929. Serial No. 343,657.

My invention relates to grates for burning coal and particularly to grates for burning very fine coal, such as No. 1 buckwheat and smaller, without a forced draft, although a forced draft may be used if desired.

Grates of the ordinary type used for burning coal in larger sizes are not adapted for burning coal of the buckwheat and smaller sizes because the spacing between the grate bars is so great that the finer coal drops through into the ash pit. When the spacing of the grate bars is decreased so that the coal does not fall through, the available space for the passage of air is cut down to such an extent that the coal cannot be burned without a forced draft. When both the spacing and thickness of bars of the present types are reduced, the grate, because of its comparatively delicate structure burns and warps unless kept cool by some forced draft. For these reasons, it has not been practicable to burn buckwheat or finer coal with a natural draft in residences having chimneys of ordinary height. Furthermore, the maximum volume of air which it is possible to pass through grates of the present type adapted for burning the finer sizes of coal is insufficient to provide the high rate of combustion which, in many instances, is desired.

One of the objects of my invention, therefore, is to provide a grate which will satisfactorily and economically burn the finer sizes of coal without a forced draft and with a chimney of ordinary residential height. Another object is to provide a grate of such character that when used with forced draft or induced draft such as in a locomotive, steam vessel or industrial plant, these finer sizes of coal may be burned at a much higher rate than is now possible with present type grates. Another object is to provide a grate of this character having substantially no surfaces upon or between which ashes may accumulate. Another incidental object is to provide a grate for a furnace having a circular fire pot in which there will be no openings of such a large size that fine particles of coal can fall therethrough into the ash pit. Another object is to provide a grate having a minimum amount of metal therein and having this

metal disposed so that while there are only extremely small areas in contact with the fire there are extremely large superficial areas exposed to incoming air currents. Another object is to provide a grate which is particularly adapted for burning the finer sizes of coal and in which the ratio of air space area to metal area in the upper surface of the grate is considerably higher than in grates of the type now used. Another object is to provide a grate which, while particularly adapted to burn extremely fine coal, is also adapted to burn coal of any size and may be shaken or turned in such a way as to provide openings sufficiently large for the passage of any stones, clinkers or cinders present in the fire pot. And a further object is to provide a grate through which a much greater volume of air may be passed in a given time than with grates of the present type.

I accomplish these objects by the means and in the manner described in the following specification and illustrated in the accompanying drawings in which—

Fig. 1 is a plan view of my grate adapted for a furnace having a round fire box;

Fig. 2 is a section of Fig. 1 in the plane 2—2;

Fig. 3 is a section of Fig. 1 in the plane 3—3;

Fig. 4 is a section of Fig. 1 in the plane 4—4;

Fig. 5 illustrates my grate as adapted for a furnace having a rectangular fire box;

Fig. 6 is a section of Fig. 5 in the plane 6—6; and

Fig. 7 is a fragmentary perspective view of a section of a stationary grate.

Referring to the drawings, my grate, when circular or square, preferably comprises four sections carried by the supporting bars, 1, 2, 3 and 4, and assembled upon which, or preferably cast integral therewith, are the fins represented generally in Figs. 1, 2, 3 and 4, by the numeral, 5, and in Figs. 5 and 6 by the numeral, 5'. Where the grates are to be used with a furnace having a rectangular fire box, all of the fins may be similar, as shown in Figs. 5 and 6. In either the round or rectangular species of grate, these fins are

- extremely thin plates of metal, and preferably but not necessarily decrease in thickness from the top to a comparatively sharp edge having no substantial thickness at the bottom.
- 5 The fins in any case are comparatively deep so that the sides of each present heat radiating surfaces of substantial area to the incoming air. The supporting bars are of course round where they pass through the sides of
- 10 the fire box so that they may be turned in shaking, but the cross section, within the space occupied by the fins, is preferably quite steeply sloped upon the top as shown in Figs. 3 and 6 so that ashes will not rest thereon.
- 15 It will also be noted that the bars 1, 2, 3 and 4, and the bars, 1', 2', 3' and 4' are spaced somewhat below the upper edges of the fins.

The fins should in all instances, be very thin at the top, for example, not over one-fourth 20 inch, and preferably one-eighth of an inch or slightly less in thickness, and the clear spaces between the bars, at the top, should always be substantially wider than the thickness of the bars thus assuring a ratio of air 25 space to metal in excess of 1 to 1. Where No. 1 buckwheat, for example, is to be burned, it has been found in practice that fins one-eighth of an inch thick at the top and spaced as wide as five-sixteenth of an inch will give 30 highly satisfactory results. In this case, if the fins are tapered the spaces between the fins at the bottom are about seven-sixteenths of an inch so that ashes passing the spaces at the top will readily fall through when the 35 grate is agitated and will not become clogged between the fins.

Where the grate is intended for use with a furnace having a rectangular fire box there may be as many separate elements as are necessary, and each element of the grate as well as the fins may be alike, as shown in Fig. 5. Where the grate is intended for use in a circular fire box each one of the grate elements is necessarily different. In the latter case, 45 the outer edges of the fins associated with supporting bars, 1 and 4, are arranged in a circular arc as are also the edges of several of the fins at each end of bars, 2 and 3. As shown in Figs. 1, 2 and 4, the extreme fins 50 at each end of the supporting bars, 2 and 3, are provided with projections, 7, disposed at right angles to the end fins so that no large space remains here between the grate and fire space. The spaces, 6, between the separate sections of the grate should, of course, conform 55 substantially to the spacing of the fins.

Where the grates consist of four separate, main elements, as shown in Figs. 1 and 5, the usual gear wheels, 8 and 9, which mesh together, and 10 and 11, which mesh together, 60 are provided on the front ends of the supporting bars. Bars, 2 and 3, are also squared at the ends, as shown at 12, to receive a shaker handle.

65 The particular configuration of the fins is

not important but where a grate of the "rocking" type is to be provided, the fins, below the plane of the fire, must be of such shape as to provide the necessary clearance in dumping or shaking. For this reason, and because 70 it is preferred to keep the metal content as low as possible, the best form of fin is believed to be approximately triangular and about in the proportions shown.

By making the fins extremely thin, and 75 thinner than the spaces between, it is possible to provide a grate having an unusually large air surface as compared to the metal surface in the plane of the top of the grate. Where the grates are made to the dimensions mentioned above as suitable for burning No. 1 buckwheat, the air surface is practically 80 75% of total grate surface and the metal area is only 25%. In other words, there is three times as much air as metal. This makes it 85 quite possible to burn very fine coal with the natural draft available in the chimney of the ordinary dwelling. Furthermore, the extremely high radiation from the fins serves to preheat the air fed to the fire and some increased efficiency in combustion is attained 90 in this way.

By making the fins extremely thin and very deep to provide large heat-radiating or cooling surfaces, all warping or burning of the 95 grate is avoided, and although such a grate is rather delicate in appearance it is, on account of its relatively great depth, in fact extremely durable and serviceable.

By gearing the supporting bars together, 100 as illustrated, it is obviously possible to move the grate elements so that comparatively large spaces are opened between them. It will be apparent, therefore, that such a grate is in nowise limited to burning a fine size of 105 coal, and while particularly adapted for the smaller sizes of coal may be used with any fuel of any size.

In many instances where the ashes are removed by raking instead of shaking a movable grate is not essential. In such cases a design similar to that shown in Fig. 7 may be used. Here, the bars or fins are comparatively long and substantially rectangular when viewed from the side. They are preferably tapered to substantially no thickness at the bottom and are made deep enough to withstand the vertical load thereon when considered as beams, as well as to provide large cooling surfaces.

It may be pointed out that the tapering of the fins to substantially no thickness at the bottom has especial advantages particularly in a grate of the rocking type because the sharp edges tend to cut or break up any 115 clinker which may be formed on the surface of the grate, instead of merely lifting such clinker or fused material and permitting it to fall back to its original position when the 120 grate is rocked.

While I have described my invention in its preferred embodiment it is to be understood that the illustrations are typical only and that the words which I have used are words of description rather than of limitation, and that changes, within the purview of the appended claims, may be made without departing from the true scope and spirit of my invention in its broad aspects.

5 What I claim is—

10 1. A grate for burning coal of the finer sizes, such as buckwheat, without material loss by falling through, comprising a plurality of parallel, very thin but deep fins having their maximum thickness at the top to form a supporting surface for the fuel, and characterized by having said fins closely spaced in the plane of the top but having the thickness of said fins in said plane less than the space between said fins in said plane whereby the minimum aggregate cross sectional area of the air spaces substantially exceeds the maximum aggregate cross sectional area of metal throughout the grate.

15 2. A grate for burning coal of the finer sizes, such as buckwheat, without material loss by falling through, comprising a plurality of parallel bars provided with very thin but deep transverse fins having their maximum thickness at the top to form a supporting surface for the fuel, and characterized by having said fins closely spaced in the plane of the top but having the thickness of said fins in said plane less than the space between said fins in said plane whereby the minimum aggregate cross sectional area of the air spaces substantially exceeds the maximum aggregate cross sectional area of metal throughout the grate.

20 3. A grate for burning coal of the finer sizes, such as buckwheat, without material loss by falling through, comprising a plurality of parallel bars provided with very thin but deep transverse fins cast integral therewith and having their maximum thickness at the top to form a supporting surface for the fuel, and characterized by having said fins closely spaced in the plane of the top but having the thickness of said fins in said plane less than the space between said fins in said plane whereby the minimum aggregate cross sectional area of the air spaces substantially exceeds the maximum aggregate cross sectional area of metal throughout the grate.

25 4. A rocking grate for burning coal of the finer sizes, such as buckwheat, without substantial loss by falling through, comprising a plurality of rotatably mounted, parallel, supporting bars provided with a multiplicity of very thin but deep transverse fins decreasing both in width and thickness from a maximum at the top and forming a supporting surface for the fuel; said fins having comparatively sharp, knife-like edges whereby 30 clinkers are cut and broken up when the

grate is rocked; and said grate being characterized by having said fins closely spaced in the plane of the top but having the thickness of said fins in said plane less than the space between said fins in said plane; whereby the minimum aggregate cross sectional area of the air spaces substantially exceeds the maximum aggregate cross sectional area of metal throughout the grate.
